UNITED STATES PATENT OFFICE.

JULIUS ROEVER, OF NEW YORK, N. Y.

SPRING-BED.

1,126,870.

Specification of Letters Patent. Patented Feb. 2, 1915.

Application filed September 26, 1913, Serial No. 791,908. Renewed September 15, 1914. Serial No. 361,922.

To all whom it may concern:

Be it known that I, JULIUS ROEVER, of the city of New York, county of Queens, and State of New York, have invented a new and useful Improvement in Spring-Beds, of which the following is a full, clear, and exact description.

My invention relates to improvements in spring beds, and the general object of my invention is to produce a spring bed which has more resiliency than the ordinary spring bed, which gives to the bed when it is made up the appearance of having a box-spring, which has its parts constructed and arranged so that they can all be made duplicate and the bed assembled in a manner to produce an inexpensive bed, which is applicable to a great variety of purposes such as ordinary spring beds to support a mattress, crib beds, seats for cars, chairs, etc., and which is absolutely sanitary.

My invention is further intended to produce a spring bed in which great strength is produced relative to the amount of metal used, and in which the resilient portions of the spring are spaced apart from the head and foot portions of the bed, thus giving to the whole bed unusual surface springiness and adapting the springs in such a manner that the bed will meet the various positions and depressions of the body.

My invention is further intended to produce a spring bed which when used as a double bed enables a surface portion of one side of the bed to be made lighter than the other, so that each part of the bed will be adapted to support different weights, and also to construct and arrange the parts so that if more than one person sleep in the bed, the movements of one body and corresponding part of the spring supports, will not affect the spring supports of the opposite part of the bed and disturb the person lying thereon.

Reference is to be had to the accompanying drawings forming a part of this specification, in which similar reference characters indicate corresponding parts in all the views.

Figure 1 is a broken plan view of the spring bed embodying my invention, one-half of the bed being removed. Fig. 2 is a diagrammatic longitudinal section showing the arrangement of the extensible springs in the bed surface. Fig. 3 is a side elevation of the spring bed as shown in Fig. 1. Fig.

4 is a detail cross section. Fig. 5 is an enlarged plan view of one of the spring saddles and its connection with the adjacent straps and braces. Fig. 6 is a broken enlarged sectional view showing a means for seating the bed on a bedstead. Fig. 7 is an enlarged detail view of a form of support for the bed. Fig. 8 is a side elevation of a modified form of the bed. Fig. 9 is a plan view of the bed as applied to a crib. Fig. 9^a is a detail of a part of the structure shown in Fig. 9. Fig. 10 is a broken enlarged side elevation of one of the spring saddles. Fig. 11 is an enlarged sectional detail view showing a means for supporting the bed on a bedstead, and Fig. 12 is a plan view of the modified form of bed shown in Fig. 8.

The bed is preferably made in two separable longitudinal sections each forming one-half of a complete double bed, so that the parts can be very easily assembled and either section used as a single bed, or combined with a similar section for use as a double bed. Each section which can of course be of any width, is produced with longitudinal supporting bars 10 which are preferably tubular, and these at the ends enter sections 11 (see Figs. 1 and 3), which sections carry upwardly and outwardly extending brackets 12 adapted to support the cross-bars 13 and 14 at the ends of the bed, and on the upper and lower parts thereof, these cross-bars being preferably angle irons as shown in Fig. 3. The top surface of the bed, and also preferably the lower surface, is formed of parallel flexible straps 15 in the form of links 16, which are hinged together as shown, and which are preferably, though not necessarily, rectangular, the links at the ends of the bed being hooked to the bars 13 at the top and to the bars 14 beneath, as the drawings show at 17.

At intervals along each strap formed of the connected links, and on both surfaces of the bed, are the spring saddles 18 which support the vertically arranged spiral springs 19 which form the chief spring support of the top surface. Each saddle has a flat flange portion 20 in the middle part from which is pressed a crown 21 having on opposite sides lugs 22 (see Fig. 10) and these are adapted to connect with a wire 19^a of the spring 19, so that the spring can be given a turn and its end twisted under the lugs 22 so as to firmly support the spring. It will of course be understood that

the saddles 18 at the top of the bed have the crown 21 on their under sides, while the saddles at the bottom have the crown on their top sides. The flange 20 of each saddle is perforated near the corners as shown at 23 to engage the links 16, and also to engage the guys or braces 24 which extend diagonally across from the saddle 18 of one strap 15 to the saddle of the next adjacent strap. Thus a flexible connection between the several straps is formed, and the straps have also the necessary vertical flexibility and extensibility. This extensibility is formed by the extensible springs 25 which are spiral springs arranged preferably in pairs and forming parts of the straps 15, the springs 25 being preferably connected with a link 16 at one end and with a saddle 18 at the other end, as shown clearly in Figs. 1 and 3. In Fig. 2 I have shown the arrangement of these extensible straps in a construction of bed which otherwise is old-fashioned, the links 16 being supported on plain angle irons 13, and the springs 25 being arranged midway of the bed, though they can be arranged at a plurality of points.

I am aware that it is not new to use extensible springs 25 to form a connection between the bed surface and the angle irons 13 or equivalent parts, but this does not give the effect which I desire. By having the springs 25 arranged nearer the center of the bed and adjacent to the vertical springs 19, I get a combination effect which taken in connection with the straps 15, renders the surface of the bed adapted to fit the body in all its movements, and gives extreme resiliency and also extreme strength. For instance, if one strap 15 is depressed more than an adjacent strap, the springs 19 and 25 permit it, while the cross connection through the guys or braces 24 distribute a portion of the strain of the next adjacent strap. If, however, the middle portion of the bed were left substantially non-elastic and the springs 25 were arranged at the ends of such portion, the effect described would not obtain. With the construction I have shown and described, it will be understood, too, that the parts can be easily duplicated and assembled.

Transversely of the bed it is preferable to have the under surface a little shorter than the upper surface, as shown in Fig. 4, so that when the strain is applied to the springs, the saddles 18 at the outer edges of the bed will not move out and engage the side rails 33 of a bedstead.

When the bed is used in two sections as illustrated in Fig. 1, I have the cross support formed preferably of cross-bars 26 which are arranged near the ends of the bed, and each cross-bar enters at its ends a socket 27 (see Fig. 6) which has a raised rib 28 on the upper side, and this can be

provided with a seat 29 to support the bar 10 of the spring bed and prevent its displacement, or if preferred the bar 10 can be made to rest on the bar 26 opposite the inner end of the rib 28 which will prevent the bar from moving out toward the rail 33. The object of this arrangement is to hold the bed sections so that they cannot slide out near the rail 33 and permit the springs 19 to grate against the rail 33. The rib 28 merges into a flat section 30 which is adapted to lie on the rail 33, as shown in Fig. 6.

The cross-bars 13 and 14 can at their ends be provided with brackets 31 adapted to sit on the rails 33 as shown best in Fig. 11, and the brackets can be provided with an abutment 32 to prevent displacement. When this construction is used, the cross-bars 26 can be dispensed with.

As shown in Figs. 8 and 12 I have virtually a double spring bed in which the two sections are united, and yet have independent vertical action. As here shown, it will be seen that the middle sections of the top surface of the straps 15 are not connected by the braces 24, so that the top surface presents two independent bed sections, while the whole structure is united in a single frame. This structure is modified somewhat from the structure shown in Fig. 1 also by the fact that it is provided with cross-bars 35 which are supported on the bars 10 and connected therewith by straps 36 or the like, and in this structure the cross-bars 26 are not used, but brackets 34 are affixed to the ends of the cross bars 13 and 14 to rest on the rails 33. In this form of bed the springs 19 are all preferably arranged near the center part of the bed with the extensible top springs 25 as already illustrated, but these springs 25 are omitted from the under bed surface.

In Fig. 8 I have shown a crib having the frame 37 to which the straps 15 are connected at the ends as already described, and here the under surface is omitted but cross bridges 38 are suspended from the frame 37 by means of hangers 37^a, and form supports for the springs 19 and their saddles 18, as the drawing shows. The extensible springs 25 are also arranged between the sets of springs 19 as illustrated.

From the foregoing description it will be seen that I produce a very simple form of spring having the greatest resiliency and strength, and that it is constructed in such a manner that it will cost no more than any good bed, and further that the structure can be easily adapted to the purpose of making car or other seats.

I claim:

1. A spring bed comprising a frame, top and bottom surfaces formed of flexible straps, with spiral springs longitudinally

- arranged and forming a part of the straps, said springs being spaced apart from the end portions of the bed, and vertically arranged spiral springs connecting the upper 5 and lower surfaces of the bed.
2. A spring bed comprising a frame having upper and lower cross-bars at the ends, longitudinal bars connected with and supporting the cross-bars, and flexible parallel 10 straps connecting the two upper bars and the two lower bars of the frame, said straps having longitudinally arranged spiral springs spaced apart from the end portions of the bed and forming parts of the straps, 15 and vertically arranged spiral springs connecting the upper and lower straps.
3. A spring bed comprising a frame having upper and lower end cross-bars, flexible straps connecting the two upper and the 20 two lower cross-bars, said straps being formed of open connected links, extensible springs arranged in pairs and connecting certain links of the aforesaid straps, said springs being spaced apart from the end 25 portions of the bed, and vertically arranged spiral springs connecting the upper and lower straps at intervals.
4. A spring bed comprising a frame, parallel flexible straps connecting the upper 30 portions of the frame and forming the top surface of the bed, similar straps connecting the lower portions of the frame and forming the bottom surface of the bed, extensible springs spaced apart from the end 35 portions of the bed and forming parts of the aforesaid straps, vertically arranged springs connecting the upper and lower straps, and guy rods or braces connecting the adjacent straps.
- 40 5. In a spring bed, the combination with the bed surface, of a saddle having a flat flange portion, a raised crown, and outwardly extending lugs on the crown, said saddle being adapted to form a seat for spiral springs.
- 45 6. A spring bed comprising a frame having longitudinal bars, brackets at the ends of the said longitudinal bars, cross-bars supported on the brackets, flexible straps connecting the two upper cross bars and 50 the two lower cross bars, extensible springs forming portions of the straps, and vertically arranged spiral springs connecting the upper and lower straps.
7. The combination with a spring bed 55 frame having longitudinal supporting bars, of the cross-bars to support the spring bed, said cross-bars having abutments thereon to engage the longitudinal bars of the bed springs, and said cross-bars having also 60 projecting brackets to engage the rails of a bedstead.
8. A spring bed comprising a frame, upper and lower flexible straps forming the upper and lower bed surfaces, extensible 65 spiral springs spaced apart from the end portions of the bed and forming parts of the straps, vertical springs arranged between the upper and lower bed surfaces, and upper and lower saddles for the vertical 70 springs, the saddles being connected to the aforesaid straps.
9. In a structure such as described, the combination with the upper and lower flexible straps forming upper and lower surfaces 75 of the bed, of flanged saddles connected to the straps and provided with raised crowns, and vertical spiral springs arranged between the opposed saddles and seating over the crowns of the saddles.
10. The combination with the upper and lower flexible straps, of the saddles connected with the aforesaid straps, spiral springs seated on the saddles, and cross rods or guys connecting the upper saddles of adjacent straps and the lower saddles of adjacent straps, the lower guys being shorter than the upper guys, whereby the inner edges of the outer row of saddles on the lower surface of the bed are normally raised. 85 90
